UNITED STATES PATENT OFFICE

ELMER A. SPERRY, JR., OF BROOKLYN, NEW YORK, ASSIGNOR TO SPERRY GYROSCOPE COMPANY, INC., OF BROOKLYN, NEW YORK, A CORPORATION OF NEW YORK

DESIGN FOR AN AIRCRAFT LEVEL INDICATING DEVICE

Application filed October 7, 1931. Serial No. 41,327. Term of patent 14 years.

To all whom it may concern:

Be it known that I, ELMER A. SPERRY, Jr., a citizen of the United States of America, residing at Brooklyn, in the county of Kings and State of New York, have invented a new, original, and ornamental Design for an Aircraft Level Indicating Device, of which the following is a specification, reference being had to the accompanying drawing, forming a part thereof.

Fig. 1 is a front elevation of the article, showing my new design.

Fig. 2 is a side elevation of the article.

In the drawing, the background is shaded to represent the light blue of the sky, being made of a darker color toward the bottom. The representation of the airplane is of a

light cream color or white outline, the wings being radium painted. The horizontal bar across the center of the instrument, representing the horizon, in back of the representation of the airplane is also of light cream color or white and radium painted as are also the triangular indexes at each side of the instrument in line with the wings of the miniature airplane. The border of the face as well as the support for the representation of the airplane is of a dull color.

I claim:

The ornamental design for an aircraft level indicating device as shown and described.

In testimony whereof I have affixed my signature.

ELMER A. SPERRY, JR.
